UNITED STATES PATENT OFFICE.

WILLIAM BELL WHITE, JR., OF COLNE, ENGLAND.

DOBBY FOR LOOMS.

SPECIFICATION forming part of Letters Patent No. 643,021, dated February 6, 1900.

Application filed March 18, 1899. Serial No. 709,670. (No model.)

To all whom it may concern:

Be it known that I, WILLIAM BELL WHITE, Jr., a subject of the Queen of Great Britain, residing at Colne, Lancaster county, England, have invented certain new and useful Improvements in Dobby Mechanism for Looms, of which the following is a full, clear, and exact specification.

This invention relates to improvements in dobbies of that class in which hooked U-shaped spring-catches are employed for lifting the jacks. Hitherto in this type of dobbies two pattern-cylinders have usually been employed, the pegged lags of which have acted direct on the catches, thus necessitating a double reading of the pattern and involving a considerable complication of the working parts.

The object of the present invention is to simplify the mechanism by the employment of a single pattern-cylinder arranged to act on T-shaped needles, which are operated by the pegged lags of the pattern-cylinder in such a manner as to throw the hooked extremities of the U-shaped spring-catches into position to be raised by the lifting-knives of the dobbies.

According to my present invention I employ two U-shaped spring-catches having hooked extremities, one leg of the U being preferably longer than the other. The short hooked end rests on a stationary projection. Two of these spring-catches are mounted at their U-bends on a small stud on the jack-lever, one of the said catches being in advance of the other. The studs are on each side of the jack. The said T-shaped needles are arranged to slide in grooves and are operated upon by the pegged lags of a single pattern-cylinder, and the needles are alternately long and short, the projecting extremities of the long needles acting upon the more distant spring-catches, while the short needles act upon the near catches to bring them alternately in position to be operated by the lifting-knives, as the case may be, according to the pegging of the lags, and thus retain any particular jack in position for any required number of picks. The hooked extremities of

the U-catches are preferably pushed into action by the pegs of the pattern-cylinder forcing forward the needles. The U-catches spring back into their normal position when the lifting-knife has been lowered. The arrangement may, however, be reversed, the catches being forced out of action by the needles and springing into position on the absence of the peg. I preferably employ double jack-levers arranged in a peculiar and novel manner. The first jack-lever—i. e., the one carrying the spring-catches—is pivoted at one end and at the other the stave is attached. In the center on each side are the studs, on which are mounted the spring lifting-catches. The other lever is reversely pivoted at one end and at the other end the stave is attached. A central connection is made between one lever and the other, so that they will be simultaneously lifted and at the same time lift the healds. In a modification the lower lever carries the spring-catches and is formed on its upper edge with a swell which bears against a projection formed on the under side of the upper jack-lever, so as to cause a simultaneous lift of the levers when the lower lever is raised by the needles, thus dispensing with the links or hooks.

My invention further relates to improved mechanism for operating the lifting-knives of dobbies, with the object chiefly of preventing a smash or breakage of the working parts in case anything gets stuck fast. On the dobbies-frame I mount a two-armed lever, which has a rocking movement imparted to it by the usual rod, operated from a suitable tappet or treadle from the tappet-shaft of the loom. At or near each end of the armed levers I mount a forked or slotted arm, its forked end passing through a bridge-piece and being provided with a bowl, which rests on the end of the two-armed lever, while its other end is connected to the lifting-knife. Both forked arms are similarly arranged by being connected to the respective lifting-knives. Should anything get stuck fast in the working parts, the two-armed lever will continue to work without doing damage, the same being free to move in the forked ends of the arms or levers connected to the lifting-knives.

In the accompanying drawings, Figure 1 is a detailed view of my improved dobbies, show-

ing the means for actuating the jack-levers. Figs. 2 and 3 are front and back views, respectively, of the dobbey; and Fig. 4 is an end view thereof, showing the means for operating the lifting-knives.

Referring to Fig. 1, A and B are the U-shaped spring-catches, each of which is made with a long and a short leg. The long leg projects upward and is formed with a catch 10 extremity E, while the short leg is also formed with a bent end or catch F, which rests on a cross-bar of the grate G when in its normal position. The grate G is secured to the inner sides of the dobbey-framing, as shown in Fig. 15. The spring-catches are secured at the bent lower end portions of their long and short legs to the jack-lever C by studs D, as shown.

H and J are T-shaped needles, which are 20 acted upon by the lattice-pegs on the pattern barrel or cylinder K. The needles are notched, as shown, to limit their movement in the grate L, which is also shown in the framing. The long needles J act upon the spring-catches B, while the short needles H act upon the catches 25 A. The needles are supported in the grates I and L, the grate L also serving as a guide for the spring-catches A and B, as shown.

In Fig. 3 the jack-levers C, which carry the 30 spring-catches, are pivoted at M and their other extremities move in the grate N. From 35 jack-levers C a central link or connection a is made to the jacks C', pivoted at P, so that on the lifting of the jacks C jacks C' will be simultaneously lifted, and consequently the 40 healds attached to them will be raised. The jacks C' work in the grate P'. The links individually consist of two side plates or blades, which are braced together at the top and bottom by a small stud carrying a small anti-friction-bowl, which rests in an indent in the 45 jack-levers C and C'.

In Fig. 1 the links a and antifriction-bowls shown in Fig. 3 are dispensed with, and the 50 jack-levers are so mounted and constructed that on the raising of the lower jack-lever it will simultaneously raise the jack-lever above it. In this view the U-shaped spring-catches A and B are shown secured to the lower jack-lever C', pivoted at M. The jack-lever C above it is reversely pivoted at O. On the lower 55 jack-lever C' is formed a swell or lug O', which when the lower jack-lever is raised by the U-shaped spring-catches A and B in the manner described bears against the projection N, cast upon the under side of the jack-lever C, thereby raising the said lever C' simultaneously with the lever C. By this means I am enabled to obtain an equal lift of the healds or harness attached to the jack-levers in the usual manner. The ordinary toothed jack-levers soon 60 get worn in the teeth, which allows them to drop and give all manner of sheds, which objectionable feature is got rid of by my present arrangement.

65 I will now proceed to describe the action of my improved dobbey. Just according to

the pegging of the lags on the pattern-cylinder K the needles H and J will, as the case may be, thrust forward the spring-catches A or B, so that their catch extremities E will 70 come into position to be raised by the lifting-knives Q and R of the dobbey, pivoted at Q', as shown in Figs. 2 and 4. When the needles H and J are relieved from the lattice-pegs on the pattern-barrel K and the spring-catches 75 A and B are released, the spring-catches will spring back out of active position, as shown in dotted lines in Fig. 1. At the same time the spring-catches will cause the return of the needles H and J in readiness to be acted 80 upon by the succeeding pegs of the lattice-barrel. A projecting lip on the said needles limits their return movement by coming against the rod H', as shown.

The operation of the lifting-knives Q and 85 R will next be described. This is effected by rocking lever V, mounted on the stud V', as illustrated in Figs. 2 and 3. This rocking lever is actuated by connecting-rod W, operated from an eccentric or crank on the tap-pet-shaft of the loom in the usual manner. Rocking lever V gives an alternate movement to two arms X, whose ends are passed through slotted brackets Y in rocking lever V and are supported upon the same by bowls Z, 95 which rest in a slot, groove, or indenture formed in the top edge of such lever. The arms X are connected to respective lifting-knives Q and R, which they operate.

It will be evident that should any working 100 part get stuck fast the rocking arm V will continue to work independently of the arms X, thus preventing any damage.

The lifting-knife R, about midway of its length, has attached to it a branch arm R'. 105 This branch arm R', with the fall or gravity of the arms X, on being relieved from the rocking lever V operates the two-armed lever S, pivoted at S'. (See Fig. 3.) The other extremity of the lever S is connected to another 110 two-armed lever T, centrally pivoted on the shaft T' of the pattern-barrel K. Fixed to the lever T is a small link U, carrying pawl or catch U', which engages with the ratchet-wheel K' and turns pattern-barrel K, a small 115 blade-spring B' keeping the catch U' in gear with the said ratchet-wheel.

Having thus described my invention, what I claim is—

1. The combination, in a loom-dobby mechanism, of the jack-lever having lateral studs, the vertical spring-catches each formed with a long and a short leg having hooks at their upper ends and joined at their lower ends by a bend engaged with one of said studs on the 120 jack-lever to raise the latter, a second jack-lever engaged with and raised by the afore-said jack-lever, the fixed grating on which the hooked ends of the short legs of the spring-catches normally rest, the lifting-knives, the 125 horizontal T-shaped needles having their inner ends bearing against the long legs of the 130

spring-catches to push them into the paths of the lifting-knives, and the pattern-cylinder for advancing said needles, the spring-catches by their resiliency springing back and restoring the needles to normal position when the needles are relieved from the action of the pattern-cylinder, substantially as described.

2. The combination in a loom-dobby mechanism, of the vertically-reciprocating knives ¹⁰ Q and R, lever devices for operating the knives, the upright spring-catches A and B, having arms of different lengths, the longest arms constructed to be engaged with and raised by said knives, the horizontal reciprocating needles H and J, acting on the long arms of the catches to throw them into the paths of the knives, a pattern-cylinder K, for operating the needles, the jack-lever C', connected with and raised by said spring-catches ¹⁵ and the jack-lever C, engaged with and raised

by the aforesaid jack-lever, substantially as described.

3. The combination in a loom-dobby mechanism, of the spring-catches Q and R, having arms of different length, the horizontally-reciprocating needles H and J, acting on the long arms of the catches, the vertically-reciprocating knives Q and R, for engaging and raising said catches, the rocking knife-operating lever V, having brackets or guides Y, ²⁵ and the arms X, connected with said knives, bearing against said rocking lever and passing loosely through said brackets or guides.

In testimony whereof I have hereunto set my hand in presence of two subscribing witnesses.

WILLIAM BELL WHITE, JUNIOR.
